UNITED STATES PATENT OFFICE.

ERNST V. HILL, OF WORCESTER, MASSACHUSETTS, ASSIGNOR TO NATIONAL SALES MACHINE COMPANY, OF BOSTON, MASSACHUSETTS, A CORPORATION OF MASSACHUSETTS.

COIN-SELECTOR.

1,354,648.

Specification of Letters Patent.

Patented Oct. 5, 1920.

Application filed March 8, 1919. Serial No. 281,330.

To all whom it may concern:

Be it known that I, ERNST V. HILL, a subject of the King of Sweden, residing at Worcester, in the county of Worcester and 5 Commonwealth of Massachusetts, have invented a new and useful Improvement in Coin-Selectors, of which the following, together with the accompanying drawings, is a specification.

10 The present invention relates to devices for separating standard coins of a predetermined denomination from counterfeits, slugs, washers, and other spurious disk-like bodies of generally similar dimensions. The

15 present improvements are applicable to the type of coin selector fully illustrated and described in the United States Letters Patent to Reith, No. 1,236,870, dated August 14, 1917, and also in my copending applications

20 Serial No. 261,797, filed November 9, 1918, and Serial No. 268,714, filed December 28, 1918.

The present invention embodies, in addition to the fundamental principles of the selector set forth in my aforesaid copending applications, certain novel principles relating to the accurate measurement and caliperizing of coins that are especially useful in connection with pieces of ten cent 25 denomination, both of the old and the new United States coinage. In common with the machines of the Reith patent and my aforesaid copending applications, the machine of the present invention is constructed 30 on the duplex principle, *i. e.*, being so designed as to accept standard coins of the same denomination, but of two different sets of dimensions. The machine of the present invention differs from the machines of my 35 aforesaid copending applications only as regards the construction, arrangement, and principle of operation of the several coin measuring and caliperizing instrumentalities, and consequently, the description and drawings of the present application will be confined, as far as possible, to the instrumentalities wherein such differences exist.

Figure 1 is an enlarged vertical section illustrating the coin measuring and caliperizing instrumentalities that constitute the essence of the present invention.

Fig. 2 is a section on line 2—2, of Fig. 1, and

Fig. 3 is a detail view of one of the 55 measuring members.

Like reference characters refer to like parts in the different figures.

The detector mechanism in the present machine is carried in the usual elongated casing 1, which contains, as in the machines 60 of the Reith patent and my aforesaid copending applications, a stationary cylindrical barrel 2 and a movable cylindrical barrel 3. These barrels provide the similar co-operating sets of coin measuring instrumentalities that constitute the subject matter of the present invention; the varying amounts by which said instrumentalities are moved are availed of to control the position of opposite pairs of pendulums 4, 5 and 6, 7, of the same character as the pendulums 65 provided in the machines of the Reith patent and my aforesaid copending applications. The ends of said pendulums are adapted to coöperate with suitable sets of 70 wards and recesses carried by a pair of valve controlling levers 8, 8, one adapted for movement in the case of a standard coin of one set of dimensions, and the other adapted for movement in the case of a standard coin 75 of the same denomination, but of a different set of dimensions, as in the machines of the Reith patent and my aforesaid copending applications.

Said levers 8, 8 are operated upon by a 85 spring 9 and at their ends are normally in engagement with a cam 10 on shaft 11, the rotation of which is communicated to the movable barrel 3 by means of a connecting link 12, sleeve 13, spring 14 and plate 15, 90 in precisely the same manner as described in the Reith patent and in my aforesaid copending applications. The position assumed by the pendulums 4, 5 and 6, 7 and also the positions assumed by a pair of thickness 95 pendulums, not shown, that are controlled by the co-operating annular knife edges 16 of said barrels 2 and 3, are the determining factors in the movement of one or the other of the levers 8 against the low portions of 100 cam 10. If the coin undergoing measurement is correct, one or the other of the levers 8 will be allowed to move upwardly by said pendulums, and this movement is transmitted to a pivoted coin directing valve 17, that 105 operates to procure acceptance of the coin, as in the machines of the Reith patent and my aforesaid copending applications. On the other hand, if the coin is spurious or does not correspond to either of the two sets 110

of dimensions contemplated by the machine, neither of the levers 8, 8, is allowed to move, and the valve 17 is held in such a position as to reject said coin. The instrumentalities which constitute the subject matter of the present invention and to which the movements of the several pendulums are delicately responsive, will now be described in detail.

- 10 Each barrel 2, 3 contains a plunger 18 which is of two diameters, slidably mounted in the barrel, and urged yieldingly outward by means of springs 19 bearing against shoulders 20 of said barrels. These plungers 18 contain the sets of measuring instrumentalities that make contact with the two faces of the coin when the latter is received between them, said coin being centered with respect to said plungers by means of a sliding block 21, carried by barrel 3, and said coin being gripped in said centered position by the knife edges 16, 16, precisely the same as in the machines of the Reith patent and my aforesaid copending applications.
- 15 Each plunger 18 contains a concentric slidable plunger mechanism which is constituted by a plurality of annularly arranged plunger sections or segments 22, the latter presenting an annular series of knife edges 23. Each plunger section 22 has a flange portion 24 that bears against a shoulder 25 of plunger 18, said series of flanges 24 being yieldingly held against the shoulder 25 by means of a series of springs 26, carried by studs 27 that project outwardly from said flanges 24. The springs 26 are confined at their outer ends in recesses provided in plates 28, 28 that close the end of the respective barrels 2 and 3.
- 20 The plunger sections 22 are slidable between their surrounding plunger 18 and an annular inner sleeve 29, the periphery of which is provided with a plurality of longitudinal grooves or slots, each adapted to receive a slidable member 30, Fig. 3. The inward movement of each slidable member 30 is limited by the contact of a shoulder 31 thereon with coöperating shoulder 32 of sleeve 29. Each member 30 bears at its outer end against a sliding pin 33, which latter has a collar 34 that takes the pressure of a spring 35. Each pin 33 is supported for sliding movement in the plate 28 and in a flange 36 of sleeve 29.
- 25 Said sleeve 29 in addition to its outwardly directed annular flange 36, which finds a sliding fit in plunger 18, is provided with an inwardly directed flange 37 which is adapted to slide on the inner concentric sleeve 38.
- 30 The flange 37 provides bearing holes for an annular series of gaging pins 39, as herein-after described.
- 35 The flange 36, in addition to providing bearings for the sliding pins 33, also provides clearance holes for studs 27. Said

flange 36 carries a stud 41 which is adapted to make contact with an adjusting screw 42 that is carried by a lever 43, pivoted at 44 in plunger 18. As in the machines of the aforesaid Reith patent, and my aforesaid copending applications, said levers 43, 43 are utilized to control the positions of one of said pendulums 4, 5, the longer arms of said levers projecting through slots in the barrels 2, 3, and being operated upon by springs 45. The flange 36 of sleeve 29 also is adapted to take the bearing of a spring 46, which is supported by stud 27, and confined between said flange and the flange 24 of flange section 22.

Each gaging pin 39 is slidable in the inner flange 37 of sleeve 29 and in the outer flange 47 of sleeve 38. Each pin 39 has an integral collar 48 to receive the pressure of a spring 49, which yieldingly tends to hold said collar against the outer side of flange 47. The sleeve 38, which is slidable within the sleeve 29 and plunger 18, furnishes a bearing for spring pressed center pin 50, and the flange 47 of said sleeve 38 has suitable clearance holes for studs 27 and 41. Said flange 47 receives the bearing of a spring 51, carried on stud 27 between said flange 47 and flange 24. Said flange 47 also carries a screw 52, which is adapted to make contact with an adjusting screw 53 that is carried by lever 54. The levers 54, pivoted at 55 in the plungers 18, are utilized to control the positions of the other set of pendulums 6, 7, as fully described in the aforesaid Reith patent and in my aforesaid copending applications, said levers 54 being acted upon by springs 56.

When a coin is dropped into slot 57, its downward movement is arrested by suitable devices, not herein shown, but fully described in the aforesaid Reith patent, so that it comes to rest in a central position with respect to the measuring points and edges above described. Under these conditions the coin directing valve 17 is in its normal position, namely in the position adapted to direct the coin into the compartment reserved for spurious or counterfeit pieces. The levers 8, 8 are prevented from moving under the action of spring 9, either because they are in engagement with the concentric pair of cam 10, or because the ends of one or more of the pendulums 4, 5, 6, 7, or the thickness pendulums, not shown, are opposite and in contact with the wards or projections carried by said levers.

Upon rotation of shaft 11 through slightly more than quarter of a revolution, the barrel 3 begins to move toward the barrel 2, it being noted that the movement of said shaft is transmitted through link 12 to the sleeve 13, spring 14, and plate 15, which latter first acts through springs 58 to move the block 21 toward the barrel 2, and thereafter acts to bodily move the barrel 3 in the same direc-

65 120 130

tion. This primary movement of the block 21 causes it to receive within its central cavity the coin which has been arrested in its passage through slot 57 by the arresting mechanism, not shown. The subsequent movement of the barrel 3 with its knife edges, pins and other measuring instrumentalities into engagement with the coin occurs while the shaft 11 is so moving that the link 12 is approaching a horizontal position, or during the first half of the forward movement of crank 59 on said shaft. As said movement is continued through its last half, the link 12 operates to retract the barrel 3, and the arresting mechanism, not shown, is thereupon retracted from the slot 57 so as to permit the gravity descent of the coin into the valve 17. As the barrel 3 begins its movement toward the barrel 2, by force applied through plate 15, the knife edges 16 are brought into engagement with the outer part of the coin just inside of its rim or flange, thus firmly gripping and holding the coin within the cylindrical cavity of block 21. The engagement of these knife edges with the coin determines the amount of inward movement of barrel 3, and as described in the Reith patent and in my aforesaid co-pending applications, a pair of thickness pendulums, not herein shown, since they form no part of the present invention, are made responsive to this movement in such a manner as to permit the lifting of either one of the levers 8 if the thickness thus measured corresponds to the predetermined standard, provided of course the other pendulums 4, 5 and 6, 7 will permit of this movement. These other pendulums 4, 5 and 6, 7 are controlled as above stated by the novel coöperating coin measuring instrumentalities herein described which are carried by the barrels 2 and 3 and the action of which will now be set forth in detail.

The segmental knife edges 23 of plunger sections 22 are pressed inwardly against the opposite faces of the coin for variable distances, depending upon the relief of the coin at the different points of the circle engaged by said knife edges. In other words, the various plunger sections 22 will occupy different relative longitudinal positions when their respective knife edges are in contact with the face of the coin; one of these plunger sections will obviously take up a position determined by the minimum relief of the coin on the circle engaged, and the others will take up positions determined by other degrees of coin relief on the circle engaged. That plunger portion 22 which is least moved outwardly, as determined by the minimum relief of the coin on the circle engaged by sectional knife edges 23, assumes a position which permits a limited movement of the associated plunger 18, under the

action of springs 19, which tend to keep the shoulder 25 in contact with the flange 24. This outward movement of the plunger 18 changes the position of the pivot points 44 and 55. Such a change in the positions of the pivot points 44 and 55 results in a variation of the movement of the long arms of the levers 43 and 54 that would not otherwise occur if these pivot points were held stationary, and consequently a certain control is exerted over both sets of pendulums 4, 5 and 6, 7. From the above, it will be seen that the minimum relief of the coin on the circle engaged by the knife edges 23 results in a control of either the pendulum 4 or the pendulum 5, and also either the pendulum 6 or the pendulum 7.

The next smallest measuring circle is that engaged by the ends of the pins 30, which are moved outwardly by the coin relief against the pressure of springs 35. That pin 30 which moves the least, as determined by the minimum relief of the coin on the circle engaged by said pins, will determine the amount that sleeve 29 may be moved outwardly, due to the fact that the shoulder 31 is maintained in contact with shoulder 32 under the pressure of spring 35. This limited movement of sleeve 29 with its flange 36 is transmitted through stud 41, contacting with adjustable screw 42, to rock the lever 43 about its pivot, this fact applying obviously to both levers 43, and thereby effecting a control of either the pendulum 4 or the pendulum 5, as the case may be. It will thus be seen that the minimum relief of the coin on the circle engaged by the pins 30 is availed of to control the movement of the set of pendulums 4, 5.

The contact of the coin being tested with the gaging pins 39 and with the center pin 50 causes the outward movement of said pins in varying amounts. Of these several pins 39 and 50, that which moves the least determines the amount of movement of the flange 47, since the collars 48 of said pins are yieldingly pressed against the outer face of said flange. This limited movement of flange 47 is transmitted through screw 52 to adjusting screw 53 of lever 54, and thereby serves to rock said lever about its pivot, this applying obviously to both levers 54 and thereby effecting a control of either the pendulum 6 or the pendulum 7, as the case may be. It will thus be seen that the minimum relief of the coin, as measured either by the pins 39 or by the pin 50, is availed of to control the movement of the pendulums 6, 7.

From the foregoing it will be apparent that the measurement of the coin in the present selector on each of the several circles engaged by the measuring instrumentalities, is the measurement of minimum re-

lief; as regards the pendulums 4, 5, their action is determined by the minimum relief measured by the members 30 and the plunger sections 22; and as regards the pendulums 6, 7, their action is determined by the minimum relief measured by the pins 39 and 50 and the plunger sections 22. In the present embodiment of the invention, applied to a machine of the duplex type, 10 as illustrated in the Reith patent and in my aforesaid copending applications, it is obvious that it is immaterial in what manner the coin is presented to the slot 57, whether with its head side or its tail side facing the 15 front of the machine. It is also obvious that for a given coin, such as a ten cent piece of the old United States coinage, one of the levers 8 will be allowed to rise, while for another coin of the same denomination, 20 but different measurements, such as a ten cent piece of the new United States coinage, the other lever 8 will be allowed to rise. In this respect the machine of the present invention partakes of the same duplex principle as the machines of the Reith patent and my aforesaid copending applications. Since said principle constitutes no part of the present invention, a detailed elaboration thereof is deemed unnecessary.

30 I claim,

1. In a coin selector, the combination with two sets of mechanism operative to control the acceptance or rejection of a coin, of means for determining the action of both 35 of said sets in accordance with the minimum relief of a group of points on the face of said coin.

2. In a coin selector, the combination with two sets of mechanism operative to control 40 the acceptance or rejection of a coin, of means for determining the action of each of said sets in accordance with the minimum relief of the coin on two different circles of predetermined radius.

45 3. In a coin selector, the combination with two sets of mechanism operative to control the acceptance or rejection of a coin, of means for determining the action of both of 50 said sets in accordance with the minimum relief of a group of points on said coin, and means for determining the action of each of said sets separately, in accordance

with the minimum reliefs of two different groups of points on said coin.

4. In a coin selector, the combination with 55 two sets of mechanism operative to control the acceptance or rejection of a coin, of means for determining the action of both of said sets, together, in accordance with the minimum relief of a group of points on 60 said coin, and means for determining the action of one of said sets in accordance with the minimum relief of another group of points on said coin.

5. In a coin selector, the combination with 65 two sets of mechanism operative to control the acceptance or rejection of a coin, of means for determining the action of one of said sets in accordance with the minimum relief of the coin on a circle of pre- 70 determined radius, and means for determining the action of both of said sets in accordance with the minimum relief of the coin on a circle of different radius.

6. In a coin selector, the combination with 75 two sets of mechanism operative to control the acceptance or rejection of a coin, of means for determining the action of one of said sets in accordance with the minimum relief of the coin on a circle of predeter- 80 mined radius, and means for determining the action of the other of said sets in accordance with the minimum relief of the coin on a circle of different radius.

7. In a coin selector, the combination with 85 two sets of mechanism operative to control the acceptance or rejection of a coin, of means for determining the action of one of said sets in accordance with the minimum relief of the coin on a circle of predeter- 90 mined radius, means for determining the action of the other of said sets in accordance with the minimum relief of the coin on a circle of different radius, and means for determining the action of both of said 95 sets, together, in accordance with the minimum relief of the coin on a circle of another different radius.

Dated this 26th day of February, 1919.
